LINE CONTROL

Leland S. Hamer, Long Beach, Calif., assignor
of one-fourth to Paul A. Dewhirst, Los Angeles,
Calif.

Application May 21, 1945, Serial No. 594,852

10 Claims. (Cl. 277—67)

This invention has to do with a line control and is more particularly concerned with the control of flow through a pipe line, or the like, by means of a plate in combination with gates. It is a general object of my present invention to provide a simple, effective, improved structure of the general character referred to wherein there is a plate operable to handle or control flow, either a blinding plate or an orifice plate, and in addition to the plate there are gate units one at each side of the plate so that the line can be effectively closed in either direction from the plate.

It is common, in handling fluids or in manifold assemblies to employ flow handling plates with blinding plates or orifice plates, and it is often necessary to provide a shut-off means at either side of a plate, and this is usually accomplished through the use of an ordinary gate valve. The usual assembly of a plate fitting with standard or ordinary type gate valves is cumbersome, expensive, and occupies a great deal of space.

It is a general object of my present invention to provide a simplified and improved assembly involving a plate and two gate units, one at each side of the plate, in which assembly the gate units are coupled by structure supporting the operating means for the gates, and also by independently operable means around the flow passage. With the construction that I have provided a single frame carries the nuts of the operating means that work in connection with the stems of the gates and also couples the body extensions of the gate units through which the stems pass. The construction just referred to ties or couples the gate units together so that they can be handled or manipulated as a single unit.

It is a further object of my present invention to provide a construction of the general character above referred to in which the gates of the valve units are removable from the flow passages of said units while the units are coupled or joined together.

The various objects and features of my invention will be fully understood from the following detailed description of a typical preferred form and application of the invention, throughout which description reference is made to the accompanying drawings, in which:

Fig. 1 is a longitudinal vertical detailed sectional view of the construction provided by my invention showing it in operating position in a pipe line. Fig. 2 is a reduced view of the upper end portion of one of the gate units showing an operating wrench applied thereto. Fig. 3 is a

5 sectional view taken as indicated by line 3—3 on Fig. 2. Fig. 4 is a transverse sectional view of the structure being a view taken as indicated by line 4—4 on Fig. 1. Fig. 5 is a plan section taken as indicated by line 5—5 on Fig. 1, and Fig. 6 is a plan section taken as indicated by line 6—6 on Fig. 1.

10 The construction provided by my invention involves, generally, two like opposed gate units A and B, a plate C carried between the gate units, means D connecting the gate units where the plate is engaged between them, which means is operable to clamp the gate units to the plate or to spread them to free the plate, a frame E connecting the gate units independent of the means D so the units have limited relative movement under the influence of means D, and means F carried by the frame E to effect operation of the gate units.

15 20 The gate units A and B are like opposed structures in the nature of gate valves and the units are arranged in opposed relation so that their inner ends receive the plate C between them. Since the gate units are alike except that they are 25 reversed, I will describe one of the units, it being understood that the description is also applicable to the other unit.

25 30 Each gate unit includes a body with a main tubular section 10 forming a flow passage 11, a lateral extension 12 integral with the section 10 and establishing a chamber 13 for the reception of a gate 14 when it is in its retracted position, a stem 15 entering the body preferably through the top of the extension 12 through suitable packing means 16, and means 17 detachably connecting the stem and gate.

35 40 The main section 10 is a simple, tubular element having its inner end 20 normal to the axis of the flow passage 11 and finished to engage the side of the plate C. The outer end of the section 10 is finished for connection with a pipe section L or the like. In the particular case illustrated I have shown a flange 21 on the section 10 to receive a companion flange 22 on the pipe section L and I have shown bolts 23 connecting the flanges 21 and 22. It is to be understood that, in practice, any suitable means may be provided for connecting the section 10 with a pipe line L, or the like.

45 50 The extension 12 of the body is a laterally disposed case-like part forming the chamber 13 which is transverse of and which intersects the flow passage 11. The chamber 13 is shaped and proportioned to receive or accommodate the gate 14 which is preferably a disc-shaped gate. In

the preferred construction the extension includes side walls 24, end walls 25, and a top wall 26, all integrally joined and forming a completely closed chamber 13 except where the chamber joins the passage 11.

The inner end portion of the body section 10 has a bore 27 defining the passage 11 and has a permanent finished part or surface 28 normal to the passage 11 and forming a seat or face against which the gate abuts when closed. The outer end portion of the main section 10 of the body is provided with a counterbore 29 and a sleeve 30 is slidably engaged in the counterbore and has its inner end 31 inclined or pitched relative to the passage 11 and finished to be flat and so as to form a seat for the reception of the gate 14. The outer end 32 of the sleeve is flat and flush with the outer end 33 of the section 10. The opening or bore 34 through the sleeve 30 conforms in diameter with the bore 27 and defines the passage 11 in the outer portion of the section 10.

The gate 14, as above stated, is disc-shaped and, as shown in Fig 1, it is provided with an inner side 35 which is flat and normal to the passage 11 and with an outer side 36 which is inclined or pitched relative to the passage 11 corresponding to the end 31 of the insert sleeve 30. With the construction thus far described, the faces 28 and 31 define or form a wedge-shaped opening to receive the gate and the gate is wedge-shaped to fit tightly or snugly into that opening. It will be apparent that by providing the removable sleeve and by locating that sleeve in the outer portion of the body the sleeve can be easily and quickly removed whenever desired. It is also to be observed that the gate is made of a diameter slightly smaller than the counterbore 29 in the outer portion of the body so that when it is released from the stem 15 it is free to be removed from the body by removal of the sleeve 30 from the outer end portion of the body.

The releasable connection 17 between the stem 15 and the gate 14 is designed to allow quick release of the gate from the stem when desired. The particular connection shown in the drawings involves a socket 40 in the upper or thick edge of the gate 14, and end 41 on the stem to enter the socket, and a pin 42 arranged transversely through the upper portion of the gate and the end 41 of the stem. The pin 42 is made sufficiently long so that it cannot become dislodged as it is confined by the walls 25 of the body extension 12. I provide one or more access openings 43 in the walls 24 which openings are normally closed by plugs 44 and are located so that the pin 42 can be reached for the purpose of removal when desired.

The packing means provided around the stem where it passes through the top wall 26 of body extension 12 may include a counterbore 45 in a boss 46 projecting upwardly from the top wall 26. Packing 47 is arranged in the counterbore and a follower 48 is provided for compressing the packing around the stem.

The plate C is a flow control element acting between the units A and B, that is, between the inner end faces 20 of the tubular sections 10 of the units, and in practice the plate may be of any suitable character, for instance, an orifice plate or a blinding plate. In the drawings I have shown a plate in position having a blinding end between the gate units A and B and an apertured end out of operating position. The two plate sections are joined by a neck portion 50 having an elongate opening or slot 51. The neck of the plate is held

by one of the units of means D as will be herein-after described.

In practice it may be desirable to provide means for sealing between the gate units and the plate. To this end I have shown channels 52 in the end faces 20 of the body sections 10 surrounding the portion 27 and I have provided packing 53 in the channels. It is to be understood that any suitable packing means or sealing means, such as gaskets or sealing rings, may be used in place of the arrangement I have shown.

The means D is provided for operating the units A and B relative to each other, that is, in an axial direction relative to each other, and preferably includes a plurality of spaced elements in the nature of screw devices. In the preferred arrangement I provide three units of means D spaced around the inner end portions of the body sections 10 of the units A and B by 15 which arrangement the elements of means D are spaced so that the plate parts can be swung into and out of position between them.

Each element of the means D involves lugs 55 projecting radially from the inner end portions of 20 the body sections 10 near their inner ends, a nut 56 carried in one lug, and a screw 57 carried by the opposite lug. The nut 56 is a spool-like element having an end flange 58 fitting a recess in the lug 55 so that the nut is held against rotation. 25 The nut is bodily held in a notch 60 in its supporting lug 55 and a removable key such as a cotter key 61 holds the nut in the lug.

The screw 57 is rotatably supported in a notch 62 in the other or opposite lug 55 where it is retained by a removable key 63. A head 64 is provided on the outer end of the screw to be engaged by an operating tool and a threaded end of the screw engages in the nut 56. Shoulders 65 are provided on the screw to engage opposite sides of 30 its supporting lug 55 so the screw is held against axial movement. It is also to be observed that the flanges at the ends of the nut 56 engage opposite sides of the lug 55 so the nut is held against axial movement. With the construction above 35 described, when the screw 57 is rotated in one direction the gate units A and B are drawn or clamped together onto the plate C, whereas if the screw 57 is rotated in the opposite direction the units A and B are moved about freeing the 40 plate C. One of the several screws of means D is employed to hold the plate. In the arrangement shown one of the screws 57 is located at the lower or bottom end of the structure while the other two screws are at opposite sides of the structure 45 adjacent the walls 25 of the body extension 12. One of these upper or side screws passes through the opening 51 in the neck 50 that joins the two ends of the plate so the plate can be slid and rotated to move the ends into and out of position 50 between the units A and B, as desired.

The means F provided for effecting operation of the stems 15 of the gate units involves threads 70 on the upper or projecting end portions of the stems and nuts 71 engaged on the threaded portions of the stems. The frame E, which I will hereinafter describe, supports the nuts so that they are held against axial movement but are free to rotate. When the nuts are rotated the stems threaded through them are moved axially, 65 the direction of movement depending upon the direction of rotation of the nuts. In Fig. 2 I have shown a socket wrench type of tool T to fit over the nuts and having an elongate socket 72 to receive the stems as they move upwardly.

75 The frame E that I have provided serves to

join or couple the body extensions 12 tying them together yet allowing relative movement between them under the influence of the means D, and it also serves to hold the nuts 71 as above described.

The frame E includes what I will term a lower insert 75 in the form of a block engaged between the bosses 46 which project from the tops 26 of the body extensions 12. The insert 75 is confined between the tops 26 and flanges 76 on the upper ends of the bosses 46. The frame further includes vertically disposed legs 77 one at each gate unit. Collar portions 78 are provided at the lower ends of the legs 77 and engage the bosses 46 so that the insert 75 is located between the collar portions 78, as clearly shown in Fig. 5 of the drawings. Bolts 79 extend between the collar portions 78 of the two legs at opposite sides of the bosses and extend through openings 80 in the insert 75 so that the collar portions and the insert are tied together by the bolts, and so that they are engaged around the bosses and thus couple or tie the units A and B together at the upper end portions of the extensions 12. The opposed faces 81 and 82 of the collar portions 78 and inserts 75, respectively, are shaped or proportioned so that they define a slightly elongate opening in the direction of the axis of the flow passage, thus allowing for slight relative movement of the units A and B axially under the influence of the means D.

Threaded posts 84 are pivotally carried on the bolts 79 to project upwardly therefrom and these posts pass through openings 85 in flanges 86 on the followers 48. Nuts 87 are provided on the upper ends of the posts. With this construction tightening of the nuts 87 operates the followers to compress the packing carried in the counterbores 45.

The legs 77 project upwardly a substantial distance above the construction just described and at their outer ends they are provided with head portions 90 which engage the nuts 71. An insert 91 is arranged between the two nuts 71 and bolts 92 extend between the head portions 90 and through the insert 91 coupling these parts together so that they form a frame that holds the nuts. Flanges 93 are provided on the nuts to operate in channels 94 in the head portions 90 and through the insert 91 coupling these parts together so that they form a frame that holds the nuts. Flanges 93 are provided on the nuts to operate in channels 94 in the head portions and insert so the nuts are held against axial movement. The nut engaging faces or portions of the head parts 90 and inserts 91 are shaped like the parts 81 and 82 of the collars 78 and inserts 75 so that the nuts are free to move somewhat axially of the flow passage.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. In combination, two like valve units, each valve unit including, a rigid body with a tubular flow conducting portion, a gate operable in the body laterally of said portion, and a gate operating stem projecting laterally from said portion, the bodies of the two units having spaced opposed inner ends in parallel planes, the bodies being shiftable relative to each other axially of said portions, a flow controlling plate between and

engaged by the inner ends of the bodies, means connecting the said portions of the valve units and operating them relative to each other axially of said portions to clamp them to the plate, a rigid frame connecting the valve units at a point laterally removed from the said portions, and means for operating the stems including members rotatably carried by the frame and threaded to the stems.

5 2. In combination, two like valve units, each valve unit including, a rigid body with a tubular flow conducting portion and a laterally projecting chest forming a chamber in communication with said tubular portion, a gate operable in the body laterally of said portion and into the chamber, and a gate operating stem projecting laterally from said portion and through the chamber, the bodies of the two units having spaced opposed inner ends in parallel planes, the bodies being shiftable relative to each other axially of said portions, a flow controlling plate between and engaged by the inner ends of the bodies, means connecting the said portions of the valve units and operating them relative to each other axially of said portions to clamp them to the plate, a rigid frame connecting the valve units at a point laterally removed from the said portions, and means for operating the stems including members rotatably carried by the frame and threaded to the stems.

10 3. In combination, two like valve units, each valve unit including, a rigid body with a tubular flow conducting portion, a gate operable in the body laterally of said portion, and a gate operating stem projecting laterally from said portion, the bodies of the two units having spaced opposed inner ends in parallel planes, the bodies being shiftable relative to each other axially of said portions, a flow controlling plate between and engaged by the inner ends of the bodies, means connecting the said portions of the valve units and operating them relative to each other axially of said portions to clamp them to the plate, a rigid frame connecting the valve units at a point laterally removed from the said portions, and means for operating the stems including members rotatably carried by the frame and threaded to the stems, the frame including a plurality of separate sections normally assembled together and attached to the bodies of the valve units to be supported thereby and carrying the said members to shift and rotate.

15 4. In combination, two like valve units, each valve unit including, a rigid body with a tubular flow conducting portion, a gate operable in the body laterally of said portion, and a gate operating stem projecting laterally from said portion, the bodies of the two units having spaced opposed inner ends in parallel planes, the bodies being shiftable relative to each other axially of said portions, a flow controlling plate between and engaged by the inner ends of the bodies, means connecting the said portions of the valve units and operating them relative to each other axially of said portions to clamp them to the plate, a rigid frame connecting the valve units at a point laterally removed from the said portions, and means for operating the stems including members rotatably carried by the frame and threaded to the stems, the frame being slidably coupled to the bodies of the valve units to be supported thereby.

20 5. In combination, two like valve units, each valve unit including, a rigid body with a tubular flow conducting portion, a gate operable in the body laterally of said portion, and a gate operating stem projecting laterally from said portion,

the bodies of the two units having spaced opposed inner ends in parallel planes, the bodies being shiftable relative to each other axially of said portions, a flow controlling plate between and engaged by the inner ends of the bodies, means connecting the said portions of the valve units and operating them relative to each other axially of said portions to clamp them to the plate, a rigid frame connecting the valve units at a point laterally removed from the said portions, and means for operating the stems including members rotatably carried by the frame and threaded to the stems, the frame including an insert between spaced parts of the valve units and legs attached to the insert and projecting therefrom and supporting said members.

6. In combination, two like valve units, each valve unit including, a rigid body with a tubular flow conducting portion, a gate operable in the body laterally of said portion, and a gate operating stem projecting laterally from said portion, the bodies of the two units having spaced opposed inner ends in parallel planes, the bodies being shiftable relative to each other axially of said portions, a flow controlling plate between and engaged by the inner ends of the bodies, means connecting the said portions of the valve units and operating them relative to each other axially of said portions to clamp them to the plate, a rigid frame connecting the valve units at a point laterally removed from the said portions, and means for operating the stems including members rotatably carried by the frame and threaded to the stems, the frame including, spaced parallel legs with collar portions at their inner ends engaged with the bodies of the valve units, and an insert between the outer end portions of the legs, the legs and said insert defining openings rotatably and slidably carrying said members.

7. In combination, two like valve units, each valve unit including, a rigid body with a tubular flow conducting portion, a gate operable in the body laterally of said portion, and a gate operating stem projecting laterally from said portion, the bodies of the two units having spaced opposed inner ends in parallel planes, the bodies being shiftable relative to each other axially of said portions, a flow controlling plate between and engaged by the inner ends of the bodies, means connecting the said portions of the valve units and operating them relative to each other axially of said portions to clamp them to the plate, a rigid frame connecting the valve units at a point laterally removed from the said portions, and means for operating the stems including members rotatably carried by the frame and threaded to the stems, the frame including spaced parallel legs, an inner insert between the inner end portions of the legs, and an outer insert between the outer end portions of the legs, the legs and inner insert slidably holding spaced parts of the bodies of the valve units and the legs and outer insert slidably and rotatably holding the said members.

8. In combination, two like valve units, each valve unit including, a rigid body with a tubular flow conducting portion with a laterally disposed gate chamber, a gate operable in the chamber laterally of said portion, and a gate operating stem projecting laterally from said portion, the bodies of the two units having spaced opposed inner ends in parallel planes, the bodies being shiftable relative to each other axially of said portions, a flow

controlling plate between and engaged by the inner ends of the bodies, means connecting the said portions of the valve units and operating them relative to each other axially of said portions to clamp them to the plate, and tubular inserts engaged in the tubular portions of the bodies from their outer ends and having inclined inner ends engaged by the gates operating the gates into engagement with walls of the chambers.

9. In combination, two like valve units, each valve unit including, a rigid body with a tubular flow conducting portion, a gate operable in the body laterally of said portion, and a gate operating stem projecting laterally from said portion, the bodies of the two units having spaced opposed inner ends in parallel planes, the bodies being shiftable relative to each other axially of said portions, a flow controlling plate between and engaged by the inner ends of the bodies, means connecting the said portions of the valve units and operating them relative to each other to clamp them to the plate including, screw operated ties circumferentially spaced around the tubular portions of the bodies, adjacent ties being spaced apart to pass the plate into and out of engagement between the inner ends of the bodies, a rigid frame connecting the valve units at a point laterally removed from the said portions, and means for operating the stems including members rotatably carried by the frame and threaded to the stems.

10. In combination, two like valve units, each valve unit including, a rigid body with a tubular flow conducting portion, a gate operable in the body laterally of said portion, and a gate operating stem projecting laterally from said portion, the bodies of the two units having spaced opposed inner ends in parallel planes, the bodies being shiftable relative to each other axially of said portions, a flow controlling plate between and engaged by the inner ends of the bodies, means connecting the said portions of the valve units and operating them relative to each other axially of said portions to clamp them to the plate including, screw operated ties circumferentially spaced around the tubular portions of the bodies, adjacent ties being spaced apart to pass the plate into and out of engagement between the inner ends of the bodies, and tubular inserts engaged in the tubular portions of the bodies from their outer ends and having inclined inner ends engaged by the gate operating the gates into engagement with the walls of the chambers.
